(57) **CLAIM**

What is claimed is the ornamental design for a luminaire structure, as shown and described.

DESCRIPTION

FIG. 1 is a perspective view as viewed from below of the luminaire structure showing our design;

FIG. 2 is a perspective view as viewed from above thereof; FIG. 3 is a left hand side elevational view thereof, the right hand side elevation being a mirror image thereof and therefore omitted;

FIG. 4 is a rear elevational view thereof, the front elevation being a mirror image thereof and therefore omitted;

FIG. 5 is a top plan view thereof;

FIG. 6 is a bottom plan view thereof;

FIG. 7 is a perspective view as viewed from below of the luminaire structure showing our design;

FIG. 8 is a perspective view as viewed from above thereof; FIG. 9 is a right hand side elevational view thereof, the left hand side elevation being a mirror image thereof and therefore omitted;

FIG. 10 is a front elevational view thereof, the rear elevation being a mirror image thereof and therefore omitted;

FIG. 11 is a top plan view thereof; and,

FIG. 12 is a bottom plan view thereof.

The broken lines in the drawings are directed to environment and are for illustrative purposes only.

The luminaire structure is shown with symbolic break lines along its length. The appearance of any portion of the article between the break lines forms no part of the claimed design. A separation and a bracket are used to indicate that, for ease of illustration, the precise length of the article is not claimed. The luminaire structure is not limited to the scale shown herein.

1 Claim, 6 Drawing Sheets
